ALL METAL SPRINGLESS AUTOMATIC
FAUCET AND VALVE

James C. Ross, Seattle, Wash.

Application July 24, 1934, Serial No. 736,695

2 Claims. (Cl. 251—136)

This invention relates to faucets, and particularly to improvements on my faucets for which Letters Patent have been granted to me by the United States, numbered 1,616,826 and 1,950,749, dated respectively February 8, 1927, and March 13, 1934.

Objects of the invention are to provide a simply constructed faucet which may be manufactured cheaply and adapted for general use and particularly to prevent loss of fluid and for regulating the amount of fluid that will pass through the valve thereof after manual release thereof, and which will automatically close at a given time after such release, together with adjustable means for holding said valve open after such release.

Another object is to provide a faucet and valve which will automatically cut off the flow of liquid therethrough without causing any jar or noises in the connecting pipes.

A further object is to provide a faucet and valve from which all liquid will drain when the supply is cut off and so prevent damage from freezing.

Another object is to provide a valve in the lower portion of the faucet which is to be normally held closed by the pressure of the fluid from the source of supply, also a separate free moving plunger above the valve, with a stem slidably disposed in a top cap for contact with the plunger to thereby open the valve all without packing or washers.

With these and other objects as will hereinafter appear, I have illustrated my invention by the accompanying drawing, of which:

Figure 1 is a side elevation view in section,

Figure 2 is a section view taken from below, on line 2—2 of Figure 1,

Figure 3 is a detail view of an interchangeable cap in section showing an outside latch for maintaining the plunger depressed and the valve open,

Figure 4 is a detail view of another interchangeable cap showing an outside latch in position for maintaining the plunger partly depressed, and the valve open to a less degree.

Like numerals represent like parts:

Numeral 5 represents the shell or main body of the faucet, which is preferably of cast metal, the lower end of which for usual connection with the source of liquid supply is provided with an ordinary thread 6, and the interior of which is bored from the opposite ends to provide an upper chamber 7 and a lower chamber 8.

A valve seat 9 is provided at the top of the lower chamber, and a free moving plunger 10 is slidably mounted in the upper chamber.

The valve 11 is provided with a tapered guide

stem 12 which is slidably mounted in a tapered guide passageway 13 between the chambers. The pressure of the liquid supply below the valve normally maintains the valve closed. A tubular check plug 14 is threaded into the base of the lower chamber beneath the valve to prevent the latter from falling from said chamber when liquid pressure is cut off.

A cap member 15 is removably connected to the top of the body and an actuating rod 16 is slidably mounted through said cap and provided with a head 17 for manual downward pressure thereon.

In Figure 1 I have shown such cap with an enlarged rectangular central cavity 18, and the lower part 19 of the rod enlarged in diameter 15 to slidably project through such cavity. On the lower end of said rod is a cross bar 20, longer than the width of said cavity, for latching such rod when such bar is depressed below the cavity. This is done by turning the lowered rod till the bar is positioned across the cavity as shown at 20' in Figure 2. This is only done, when it is desired to leave the rod in depressed position, for maintaining the valve open.

The body is provided with a discharge nozzle, 25 which extends from the base of the upper chamber to assure drainage to prevent freezing, and when liquid pressure is cut off from the valve it slides down to position 11' and permits the plunger to slide to position indicated by 10' when the top thereof will be lower than the roof of the nozzle to assure drainage from above the plunger.

The passageway through the nozzle is preferably constructed relatively large, to prevent any 35 retarding effect on the liquid flow therethrough, when under varying pressures. The velocity of such flow and pressure in the upper chamber is rendered uniform regardless of the pressure from source of supply by means of annular 40 interchangeable baffle plates or gauges 22, one of which is shown threaded on the outer end of the nozzle. Such plates may be provided with varying sized openings 23, for use on such nozzles when the pressure of liquid supply varies, as for 45 different faucets on different floors of the same hotel or other building, so that the flow from all such faucets will be equal. The orifice through the plates being smaller than the interior of the nozzle tends to direct the flow of fluid there- 50 through in straight lines, and also equalizes the pressure of the fluid in the upper chamber against and around the plunger.

In order to open the valve manual actuating power is applied to the head 17 whereby the rod 55

16 is depressed and the plunger thereby moved down against the valve stem till the valve 11 is opened from its seat 9. The liquid then flows into the chamber 7, and thence from the nozzle, which fits only loosely within said chamber. Where large faucets or valves are used with correspondingly large plungers it is desirable to provide ducts or passageways 24 through the 5 plungers to facilitate the flow of liquid to fill the space 25 that is created by depression of the plunger. These ducts may be formed relatively large, and various sized bushings or reducing elements 26 adjustably threaded therein to provide for varying dimensions to govern the flow of liquid to and fro therethrough. The return or upward movement of the plunger, after the 10 rod above is released, is controlled and the time of closing of the valve determined by return or 15 down flow of the accumulated liquid from the spaces 25.

The space between the top of the upraised valve stem and the lower face of the cap, is wider than the thickness of the plunger, so that a small 20 space 27 for a cushion of liquid remains above the plunger, when the valve beneath is seated, whereby all noise and vibration is eliminated 25 from the connecting pipes or plumbing.

By the application of the interchangeable caps 30 shown in Figures 3 and 4, the plunger may be fastened down to hold the valve open for such periods as may be desired for continuous flow of liquid, by means of bails 28 pivotally attached to the caps as at 29, and adapted to be swung 35 over and upon the tops 17, and there fit into depressions 30 and 31 on such tops, for holding the valve open at varying degrees.

Ordinarily however the faucets are designed and used to automatically close by reason of the 40 pressure of the liquid beneath the valve, and so cut off the flow from the nozzle automatically when the hand is removed from the top 17 of rod 16.

It will be understood that the dotted lines 10", 45 11", 12" and 20" indicate the respective positions of the plunger, valve, valve stem, and cross-bar on the lower end of the rod, when the valve is being held depressed for flow of liquid through the faucet. While the space then shown

between the valve stem and the walls of the guide passageway appears small, in practice I have found that only a small space is there required to provide a desirable flow of water both from the nozzle and up above the lowered plunger, all under ordinary city water pressure.

My faucet is specially valuable for preventing loss of water where in general use by the public, when faucets may be left open carelessly. The device may be also adapted for numerous other uses, as for regulated or measured flow when desired, and for flushometers or toilet tanks, etc. The valve may be opened by various means (not shown), as by solenoid or electrical or other mechanical means, or by floats in water tanks, etc. My faucet is preferably formed entirely of metal, and without either springs, or packing.

Having described my invention, I claim as new,

1. A self-closing faucet including a body formed with an upper chamber having a discharge outlet and a lower chamber open to service flow, a partition dividing the chambers and formed with an upwardly converging opening to establish communication between the chambers, the lower end of the opening merging into a conical valve 21 seat, a valve operative in the lower chamber for cooperation with said seat, a plunger operative in the upper chamber, a conical stem connected to the valve and engageable with the plunger, the stem being of a dimension to substantially fill the opening in the partition when the valve is closed, and to gradually increase the free space of the opening as the valve is moved away from its seat, whereby on closing the valve the free space of the opening is gradually reduced thereby serving as a gradual check for the flow of water prior to the closing of the valve, whereby to prevent wearing impact between the valve and its seat, and means for operating the plunger.

2. A construction as defined in claim 1, where- 40 in the plunger is formed with an opening establishing communication between the upper and lower surfaces of the plunger, the lower end of the opening being threaded to receive a reducing element for controlling the rate of flow 45 through the opening in the plunger as the plunger moves in a direction to permit closing of the valve.

JAMES C. ROSS.
